(74) Attorney, Agent, or Firm — Jonathan A. Bay

CLAIM

The ornamental design for a combined ceramic cooker lid handle and side shelf, as shown and described.

DESCRIPTION

FIG. 1 is a perspective view of a combined ceramic cooker lid handle and side shelf showing my new design;

FIG. 2 is an enlarged perspective view thereof;

FIG. 3 is a top plan view thereof;

FIG. 4 is a left side elevational view thereof; and,

FIG. 5 is a front elevational view thereof.

The broken lines represent boundary lines and environmental details which form no part of the claimed design.

1 Claim, 4 Drawing Sheets
